UNITED STATES PATENT OFFICE.

LEO SUNDERLAND, OF WESTMINSTER, LONDON, ENGLAND.

JOINING OR BONDING THE JUNCTIONS OF METALLIC SHEATHING OR ARMORING OF ELECTRIC CONDUCTORS.

1,173,394.

Specification of Letters Patent. Patented Feb. 29, 1916.

Application filed October 16, 1913. Serial No. 795,539.

To all whom it may concern:

Be it known that I, LEO SUNDERLAND, a subject of the King of Great Britain and Ireland, and resident of Westminster, county of London, England, have invented certain new and useful Improvements in Joining or Bonding the Junctions of Metallic Sheathing or Armoring of Electric Conductors, of which the following is a specification.

- 10 This invention relates to metallic sheathed conductors where the sheathing is squeezed or pressed over the insulated conductors in the course of manufacture, and has for its object to render such metallic sheathing electrically and mechanically continuous throughout, and with this object in view the said invention is directed to an efficient method and means for bonding the metallic sheathing at desired places, such, for instance, as junctions where the inclosed conductors are interrupted for utilization of the current, or otherwise.
- 20

The invention is illustrated by the accompanying drawings, wherein:—

- 25 Figure 1 shows a metallically sheathed insulated conductor prepared for bonding purposes in accordance with this invention; Fig. 2 shows four two-wire sheathed cables bonded according to this invention, and in readiness for joint-box attachment; and, Fig. 3 represents a sectional elevation of an eyelet hereinafter referred to.
- 30

Referring to the bonding together of the ends of enveloping sheaths inclosing elec-

tric conductors of the type seen in Fig. 1, 35 the said metallic sheathing *a* is, at the respective junctions, suitably slit and opened out into a connector portion *a'* as illustrated in said Fig. 1. The flat extremities *a'* of the sheathing which are to be bonded are 40 then overlapped, preferably in pairs which butt together—see Fig. 2—and holes *b* punched therethrough common to all portions *a'*. Eyelets *c* are inserted in said holes, and the top and bottom of the eyelet (or 45 only the top, or only the bottom) are formed with a cap or cover *d* integral or attached, which in use is pressed down to close the hole of the eyelet with the object of rendering the bond metallically and electrically 50 stronger.

Having now described my invention, what I claim as new and desire to secure by Letters Patent of the United States is:—

A joint for electric conductor casings 55 comprising conductor sheathing members having overlapping connector plates provided with a fastening receiving opening, and a fastening eyelet engaging said opening and provided with a cap member to 60 cover and close the opening.

In testimony whereof I have affixed my signature in presence of two witnesses.

LEO SUNDERLAND.
